GAS HOLDER

Filed Oct. 23, 1926

UNITED STATES PATENT OFFICE

FREDERICK H. WAGNER, OF BALTIMORE, MARYLAND, ASSIGNOR TO THE BARTLETT HAYWARD CO., OF BALTIMORE, MARYLAND, A CORPORATION OF MARYLAND

GAS HOLDER

Application filed October 23, 1926. Serial No. 143,766.

This invention pertains to gas holders and relates more particularly to that type known as waterless holders, such holders being set forth and claimed in Letters Patent to Jaggschitz, No. 1,275,696 dated August 13, 1918. In the structure disclosed in that patent a piston-like closure is employed in conjunction with the shell of the holder and a gas tight joint is effected between said member 10 and the shell by the utilization of shoes and a liquid sealing medium held in working relation with said shoes to afford a sealing effect as well as a lubricating effect between the shoes and the holder.

15 The present invention relates to a structure of the same general type except that a different sealing arrangement is employed and the presence or necessity of the shoes is done away with. Broadly stated, the structure may be said to comprise a shell, a piston-like closure and a felt sealing ring interposed between the piston-like closure and the inner face of the shell, means being provided to properly lubricate the sealing device.

20 The invention is illustrated in the annexed drawings wherein,

Figure 1 is a vertical sectional view of a portion of a waterless gas holder, the closure and the sealing means employed between the two, taken on the line I—I of Figure 3;

Figure 2 a vertical sectional view taken on the line II—II of Figures 1 and 3; and

Figure 3 a top plan view partly in section.

25 The gas holder proper is polygonal in outline and is composed of a series of plates 1 connected at their adjacent edges to corner posts of suitable form and shown in the instant case as formed of an inner member 2 and a stiffening supporting member 3 which may take any desired structural form. The member 2 is located inwardly of the plates 1 and heretofore some difficulty has been found 30 in effecting a tight seal about the edges of this member.

Extending outwardly from the lower portion of the piston-like closure 4 is a shelf 5, the shelf extending entirely around the 35 circumference of the closure adjacent the

lower edge thereof and terminating short of the inner face of the wall of the shell. Mounted upon and supported by the shelf is a plurality of layers of fibrous absorbent material, preferably felt, indicated by 6. 55 Layers of cloth may likewise be employed. Overlying the felt is a flexible plate 7, said plate extending inwardly and being secured by a liquid tight joint to the vertical wall of the closure 4.

The shelf and the plate 7 form, in effect, a pocket for the reception of a lubricating and sealing medium (coal tar, viscous oil, or the like) introduced into the same through pipes 8 which are connected, at their lower ends, into openings in the plate 7, the upper end of the pipes opening into a reservoir 9 secured to and carried by the piston 4. This reservoir may be a continuous one extending entirely around the closure or a plurality of separate reservoirs may be employed as may be desired. In any event, the reservoir will preferably be divided up by partitions as 10, Figure 2, in order to prevent the lubricant from running around to one side of the closure in case it should tilt slightly from the horizontal.

In order to prevent the outer edge of the plate 7 from turning upwardly and consequently allowing the felt layers to turn upwardly and out of proper contact with the wall of the holder as the piston moves downwardly, there is preferably employed a series of hold-down plates 11 which are positioned by set screws 12 mounted in the outer ends 80 of arms or brackets 13 secured at their inner ends to the wall of the piston. The plate 7 is preferably made of flexible steel so as to allow a certain give and yield in the structure.

85 Located within the reservoir or chamber formed between the shelf 5 and the overlying plate 7 and bearing against the inner edges of the felt layers are perforate plates 14 and bearing against the plates and held in proper relation thereto by the flanges upon the plates, are pressure blocks 15 urged against the pressure plates by springs 16 which surround the telescoping guide stem and post 17, as best shown in Figures 1 and 3. 90 95 100

The plates 14 are substantially co-extensive of the felt and the blocks 15 are located at intervals around the piston in sufficient number to insure the felt being moved outwardly at all times and held in such outward position in order to effect a gas tight seal between the outer edge of the felt and the inner face of the wall of the holder.

Where the felt contacts the corner posts it will be notched out, as best shown in Figure 3, so as to conform with said member and effect a tight joint not only with the face of said member 2 but likewise with the edges thereof.

The various felt layers may be stitched or otherwise temporarily secured together in order to prevent disarrangement of the layers both in initial positioning of the same and during subsequent operation of the seal.

Any suitable liquid may be employed to lubricate the felt and to afford a liquid film between the felt and the wall of the holder. The static head of the liquid will be sufficient to keep the felt impregnated at all times and no wastage of the liquid will take place as there will be no flow through the felt while the piston head is at rest but only a slight flow when the piston head is moving and the felt is placed under more or less drag at its outer edge due to such movement.

Having thus described the invention, what is claimed is:

1. In a waterless gas holder, the combination of a shell; a piston-like closure therefor; a shelf secured to the circumference of the closure and extending around the same, the outer edge of said shelf stopping short of the wall of the shell; a body of felt mounted upon the shelf; a plate overlying the felt extending inwardly and connected to the closure thereby forming a pocket; means for constantly urging the felt outwardly into contact with the wall of the shell; and a reservoir for liquid communicating with the pocket aforesaid.

2. In a waterless gas holder, the combination of a shell; a piston-like closure therefor; a shelf secured to the lower portion of the closure and extending circumferentially around the same, the outer edge of the shelf stopping short of the wall of the shell; a body of felt resting upon the outer portion of the shelf and contacting the wall of the shell; a flexible plate overlying the felt, extending inwardly therefrom and connected to the body of the closure, said plate and the shelf aforesaid forming in effect a pocket in rear of the felt; means for holding the outer edge of the plate against undue upward movement; means for urging the felt outwardly between the shelf and the plate; and a reservoir for a sealing and lubricating liquid located above and connected to the pocket.

3. In a waterless gas holder, the combination of a shell; a piston-like closure there-

for; a shelf secured to the lower portion of the closure and extending circumferentially about the same, the outer edge of the shelf stopping short of the wall of the shell; a body of felt resting upon said shelf adjacent the outer edge thereof and contacting the adjacent wall of the holder; a hold-down plate overlying the felt; means for holding said plate in proper position; a plurality of perforate plates placed against the inner face of the felt; means for pressing said plates outwardly, and a reservoir for liquid located above the felt and communicating with the pocket or chamber formed in rear thereof by the shelf and the overlying plate.

In testimony whereof I have signed my name to this specification.

FREDERICK H. WAGNER.
